AIRFOIL OR THE LIKE FOR AIRCRAFT

Siegfried Günter, Warnemunde, Germany, assignor to Ernst Heinkel, Warnemunde, Germany

Application October 12, 1938, Serial No. 234,596
In Germany June 18, 1937

9 Claims. (Cl. 244—42)

This invention relates generally to airfoils and the like for aircraft and in particular to the ailerons and special lift increasing flaps usually fitted thereon.

5 The generally known special lift increasing flaps of this type which in normal position lie below the trailing edge member of the principal wing and in lift increasing position are extended to the full chord thereof and adapted to be projected rearwardly and deflected downwardly have proved successful as landing flaps. A drawback however of this special type of flap is that hitherto it could not be utilized as an aileron so that both the special lift increasing flaps and ailerons 10 had to be fitted, and that only a portion of the airfoil benefited by the improvement in the lift conditions due to the use of said flaps. In the juxtaposed arrangement of such flaps and ailerons there is the further drawback that when the flap 15 is fully projected rearwardly the portion of the aileron nearest the flap is located in the ascending current and this causes a premature diversion of the flow at the adjacent portion of the aileron of the airfoil. Thus not only the effect 20 of the aileron but also the otherwise attainable maximum lift is reduced.

Lift increasing flaps are also known having split ailerons disposed above them. In this arrangement only decreases in lift can be obtained 25 by the aid of the upwardly deflected aileron; the aileron cannot be deflected on the other side of the airfoil and the effect of the ailerons is therefore very small in such an arrangement.

Ailerons adapted to be used as landing flaps or 30 landing flaps adapted to be used as ailerons, are also known but in these cases the flaps are invariably adapted to be swung only around a stationary axis, and as such to be deflected upwardly or downwardly, while owing to the rearward displacement and to the slot covering plate disposed above it and rigidly connected to the airfoil, the lift increasing flaps could hitherto be used only for downward deflection. The great 35 advantage of the lift increasing flaps, namely a substantial improvement of the lift conditions, was lacking in the former landing flaps which could be used as ailerons.

The invention eliminates all the aforesaid 40 drawbacks, as the upper shuttering, the mounting and the actuating devices of the lift increasing flap are so arranged that the latter can be utilized, not as hitherto only as a landing flap, but also as aileron for upward or downward deflections.

45 The invention consists in an airfoil or the

like having a rearwardly projectable flap of the mentioned type arranged below the trailing edge member thereof, wherein the said flap is upwardly as well as downwardly pivotable for use also as an aileron, both in its retracted and any 5 projected position. In this arrangement it is advantageous to have the slot closing plate hinged to the airfoil or airfoil portion in front of it, and coupled to the projectable flap or to the device controlling the said flap, so that when the 10 projected flap is deflected the trailing edge member of the airfoil moves with the flap. The coupling between the slot closing plate and the flap can be effected in a simple manner, the flap possessing guide rails or other sliding guides 15 upon which the rear edge member or other points of the slot closing flap are guided. This coupling may be so designed that the slot between the rear edge member of the closing plate and the upper surface of the landing flap varies when 20 the landing flap is projected according to aerodynamic requirements.

The essential inventive ingenuity may be expressed by saying either that a lift increasing flap can be utilized in any position as an aileron, 25 thus also for upward deflection, or that the subject matter of the invention is a rearwardly projectable aileron adapted to be utilized also as a landing flap, which in any position, i. e., both when retracted as well as in any projected position can be deflected upwardly or downwardly.

Moreover, the invention comprises a particularly suitable method of controlling the mentioned type of flap for use as an aileron. Such flaps are mostly actuated by moving them forward and backwards by means of several push rods. In many cases curved push rods are utilized, in order to obtain an enlargement of the angle of attack of the lift increasing flap when projecting it rearwardly. Also in the method of 40 control according to the invention the flap is moved by means of push rods, but to these push rods are in addition attached the operating levers for actuating the aileron, so that the said levers are also moved when the mentioned flap is being 45 projected. The aileron push rods are thus coupled to the projecting device. The advantage of this, an advantage not found in the former control for such a flap, is that without using special devices the angle of attack of this type of flap 50 increases as the flap is projected, which hitherto could be attained only by means of curved push rods, guide tracks of any desired kind, arrangements of levers and the like.

A constructional form of the invention is illus- 55

trated diagrammatically by way of example in the drawings wherein:

Figure 1 illustrates an aircraft airfoil with the flap in the retracted position.

5 Figure 2 illustrates the aircraft airfoil with the flap in the projected position.

Figure 3 illustrates a suitable constructional form of the control.

A slot closing plate *b* for the flap *c* is hinged 10 to the trailing edge of the airfoil *a*. The flap *c* is adapted to be rearwardly projected by means of the device *d* known in connection with lift increasing flaps of the type which in normal position lies below the trailing edge. The push rod 15 *e* causes the upward and downward pivoting of the flap *c*; in both illustrations three different positions of the flap *c* are outlined. On the upper surface it carries guide rails *f*, upon which the rear end *g* of the closing plate *b* slides by means 20 of rollers, studs or in other manner known per se, both when the flap is being deflected and projected rearwardly. The guide rails *f* being suitably designed for the purpose, any desired width of slot between the trailing edge member of the 25 airfoil and the flap can be obtained whenever the flap is being displaced whether forwardly or rearwardly or for the purpose of varying its angle of attack.

In Figure 3 the flap *c* is drawn in full lines for 30 the high speed flight position, and in dotted lines for the landing position. The arrangement is shown diagrammatically as seen from above. The displacing motion of the projecting push rod *d* is effected by means of a rack *h* attached on 35 the said push rod *d* and of a pinion *k* in engagement with the rack; the pinion *k* being actuated by means of the pull rope *i*. A bell crank lever *l* is pivotally mounted on the projecting push rod *d*, the aileron actuating rod *e* being attached to one arm and the rod *o* leading to the aileron push rod *n* being attached to the other arm of the said bell crank lever. The rod *e* is in the usual manner articulated to a lever arm *m* rigidly attached to the flap *c* as illustrated for 45 example in Figures 1 and 2.

The operation of the device for actuating the flap *c* both when acting as a landing flap and as an aileron may easily be gathered from the drawings, as both in the retracted and in projected 50 state several positions of the aileron bell crank are illustrated. It may further be seen from the lower position of the said bell crank *l* shown in dotted lines in Figure 3, that during its rearward projection the flap *c* already undergoes a downward deflection inasmuch as when the flap is projected the bell crank lever *l* is in a position different from the position in which it is when the flap is retracted.

As will be seen from the illustrations, the flap 60 according to the invention can be used, in the retracted and in the projected state, both as an aileron and as a landing flap. The advantage of the lift increasing flap, namely the enlargement of the airfoil area and thus also of the lift is 65 therefore also obtained by means of the invention from a landing flap adapted to be used as an aileron.

I claim:

1. An air foil for aircraft comprising a principal wing, a variable trailing edge member pivotally mounted on said principal wing, a flap lying in normal position below the said trailing edge member and in lift increasing position extended to its full chord behind the principal wing, means 70 for extending and retracting the said flap in a

substantially chordwise direction and means adapted to rock the said flap about its axis of suspension.

2. An airfoil for aircraft comprising a principal wing, a variable trailing edge member pivotally mounted on said principal wing, a flap lying in normal position below the said trailing edge member and in lift increasing position extended to its full chord behind the principal wing, guide rails arranged on the said flap and adapted to 10 guide the said trailing edge member, and means adapted to rock the said flap about its axis of suspension.

3. An airfoil for aircraft comprising a principal wing, a variable trailing edge member pivotally mounted on said principal wing, a flap lying in normal position below the said trailing edge member and in lift increasing position extended 15 to its full chord behind the principal wing, guide rails arranged on the upper surface of the said flap, means arranged on the trailing edge member and adapted to connect said edge member with the guide rails, and means to control the angular movements of the said flap.

4. An airfoil for aircraft comprising a principal wing, a variable trailing edge member pivotally mounted on said principal wing, a flap lying in normal position below the said trailing edge member and in lift increasing position extended to its full chord behind the principal wing, guide 30 rails arranged on the upper surface of the said flap, means for projecting the said flap rearwardly of the said plane and means for rocking the flap in both its retracted and its projected positions.

5. An airfoil for aircraft comprising a principal wing, a variable trailing edge member pivotally mounted on said principal wing, a flap lying in normal position below the said trailing edge member and in lift increasing position extended 40 to its full chord behind the principal wing, guide rails connected to the said flap, means arranged on the trailing edge member and adapted to couple the trailing edge member with the said guide rails, driving means to project and to retract the 45 said flap, and means connected with the driving means for the said flap to control the angular movements of the flap about its axis of suspension.

6. An airfoil for aircraft comprising a principal wing, a variable trailing edge member pivotally mounted on said principal wing, a flap lying in normal position below the said trailing edge member and in lift increasing position extended 50 to its full chord behind the principal wing, guide rails connected to the said flap, means arranged on the trailing edge member and adapted to couple the trailing edge member with the said guide rails, a push rod for projecting said flap rearwardly of the principal wing, means for actuating 55 the flap in the manner of an aileron and comprising a bell crank lever pivotally mounted on said push rod.

7. An airfoil for aircraft according to claim 6, in which one arm of the bell crank lever is connected to the flap and the other arm is connected to an actuating rod for actuating the flap.

8. An airfoil for aircraft according to claim 6, in which the push rod arranged in the principal wing is provided with a rack adapted to engage 70 with a pinion.

9. An airfoil for aircraft comprising a principal wing, a variable trailing edge member pivotally mounted on said principal wing, a flap lying in normal position below the said trailing 75

edge member and in lift increasing position extended to its full chord behind the principal wing, guide rails connected to the said flap, means arranged on the trailing edge member and adapted to couple the trailing edge member with the said guide rails, a push rod for projecting said flap

rearwardly of said principal wing, a rack attached on the said push rod and in engagement with a pinion and means for actuating the said pinion.
